Harold J. Mengel, 626 Alton Ave., Reading, Pa.

Filed Apr. 20, 1961, Ser. No. 64,831

Term of patent 14 years

(Cl. D34—5)

FIG. 1.

FIG. 2.

FIG. 3.

FIG. 4.

FIG. 5.

FIG. 6.

FIGURE 1 is a perspective view of a golf ball retrieving device in accordance with my new design and shows the same as it appears when closed.

FIG. 2 is a perspective view, similar to FIG. 1, but shows the device as it appears when in open golf ball retrieving arrangement, a golf ball being indicated in retrieved position therein by dot-and-dash lines for illustrative purposes only.

FIG. 3 is a top plan view of the device.

FIG. 4 is a front elevational view thereof.

FIG. 5 is a rear elevational view thereof, and

FIG. 6 is a bottom view thereof.

I claim:

The ornamental design for a golf ball retrieving device, substantially as shown and described.
